UNITED STATES PATENT OFFICE.

EDMUND OCUMPAUGH, 2d, OF ROCHESTER, NEW YORK, ASSIGNOR TO DEFIANCE MACHINE COMPANY, OF ROCHESTER, NEW YORK, A CORPORATION OF NEW YORK

PRINTING-MACHINE.

1,148,984.

Specification of Letters Patent.

Patented Aug. 3, 1915.

Application filed August 17, 1914. Serial No. 857,128.

To all whom it may concern:

Be it known that I, EDMUND OCUMPAUGH, 2d, a citizen of the United States, and a resident of Rochester, in the county of Monroe and State of New York, have invented 5 certain new and useful Improvements in Printing-Machines, of which the following is a specification.

This invention relates particularly to machines of the type employed in printing or impressing check-blanks with the amounts which they are to represent, and to machines for performing similar operations, particularly where, as in the case of the machine 15 known as a "check-writing" machine, the amount of the check is printed in both words and figures on the lines and in the spaces usually appropriated for these entries on a check-blank.

20 Machines of the type in question are usually provided with a type-carrier rotatable, or otherwise movable, to bring various lines of type on the carrier selectively into operative relation with a platen which coöperates 25 with the selected type-line to impress the check-blank. In some cases the type-carrier is a unitary drum or rotatable member on which the lines of type are arranged permanently, and in other cases the type-carrier 30 comprises a plurality of rotary members permitting various combinations of the characters carried thereby. In either case the platen has an elongated form so as to be co-extensive with the type-carrier and 35 with the longest line of type which may be carried thereby. In some cases, however, particularly in the case of a check-writing machine, the characters in the type-line may be so grouped as to leave a substantial space 40 at some point in the line in which there is no type to coöperate with the platen. This is particularly the case in a check-writing machine, in which a space is left in each type-row corresponding to the space on the 45 check-blank occupied by the word "dollars" customarily printed thereon. In such an arrangement there results an unbalanced pressure of the type against the platen, owing to the fact that there are more characters 50 on one side of the platen than on the other, this pressure tending to cause the platen to rock, from its normal position parallel with the type-line, sufficiently to permit a substantially greater pressure of the platen 55 against that end of the type-line which in-

cludes the fewer characters. This action results in undue wear upon the platen or the types at the end in question, and also upon the mechanism by which the platen is actuated or guided, and it also causes an unusually heavy pressure to be produced at the point in question, thus preventing the uniform and accurate impression of the entire type-line.

The object of the present invention is to 60 improve machines of the type in question by the provision of a stationary abutment so located and fixed with relation to the type-carrier and the platen that it shall be engaged by the platen substantially in the 65 same plane as the tops of the type-lines and at that part of the platen with which no type-characters coöperate owing to the grouping of these characters as above described. The effect of this abutment is to 70 produce a pressure against the platen which tends to equalize the pressure on opposite sides of the center of the platen, thus causing the coöperation of the platen with the types to be substantially uniform through 75 out the length of the type-line.

In the accompanying drawings: Figure 1 is a partial transverse, vertical section of a printing-machine embodying the present invention; and Figs. 2 and 3 are partial longitudinal sections of the same, or a similar machine, showing two different forms of 80 type-carriers.

The invention is illustrated as embodied in a printing-machine of a well-known form, 90 used particularly as a check-writing machine. This machine is provided with a flat table 5 upon which the check-blank rests, and beneath this table is a rotatable type-carrier 6 comprising one or more cylinders or 95 drums provided with lines 8 of type upon their peripheries. The work-table 5 is provided with an elongated slot 9 beneath which any one of the type-lines may be selectively brought by rotation of the type-carrier. For this purpose the type-carrier is shown as mounted upon a shaft 7 which may be turned by any suitable means, such as the hand-wheel shown in dotted lines in Fig. 1.

100 To produce an impression of the check-blank against the selected type-line the machine is provided with the usual elongated platen 10, arranged to move vertically above the slot 9 in the work-table. This platen 105

110

may be made of flexible material, such as rubber, and is shown as provided with a metal head 11 fixed, at its middle point, to a plunger 12 which moves vertically in an arm 13 overhanging the work-table. A spring 14 normally maintains the platen in raised position, but by means of a hand-lever 15 the platen may be depressed so as to force the check-blank down against the types.

10 In Fig. 2 the type-carrier is illustrated as comprising a series of rotatable members 6 which may be adjusted in a partially or wholly independent manner so as to produce

15 type-lines of a great variety by the various combinations of the groups of types on the carriers. In the case of a check-writing machine the groups of characters 18 on the first two drums 6 are arranged to express the

20 amount of a check in words, while the groups 19 on the last two drums are used to express the amount of the check in figures. In Fig. 3, on the other hand, the type-carrier is shown in the form of a single drum

25 17 upon which the lines of type are permanently arranged. It will be understood that, so far as the present invention is concerned, it is immaterial which of these two arrangements is employed in the type-carrier.

30 In the case of each of the two forms of type-carrier illustrated it will be seen that the types are so grouped in each line that there is a substantial space 20, near the 35 right-hand end of the line, where there are no types to coöperate with the platen 10. The present invention resides in the provision of an abutment at this point, this abutment being in the form of a projection 21 on the upper surface of a bar 22 which is 40 fixed transversely in the casing of the machine. This projection 21 is type-high, that is to say, its upper surface lies in the same plane as the tops of the types in the type-line which may at any time be in coöperative 45 relation with the platen. Accordingly, it resists downward movement of the platen in the same manner as do the types. Owing to the fact that it presents an unbroken surface 50 to the platen, it is not necessary that this abutment shall fill out the entire unoccupied space 20 in the type-line in order to equalize the pressure at opposite ends of the platen.

55 In the illustrated machine the types are inked by engagement with an ink-roller 23 journaled in the casing of the machine, this engagement being produced by the rotation of the type-carrier in selecting the required 60 type-line for operation. Since the abutment 21 does not receive any ink upon its upper surface it may engage the face of the check-blank, as is necessary in the performance of its functions, without producing any mark 65 or offset upon the blank.

It will be apparent that an abutment of the kind in question may be employed to fill out any part of the type-line in which there are no characters to coöperate with the platen, and while the invention is described 70 as employed in a machine in which the platen is of yielding material and the types and the abutment are of rigid material, it will be apparent that the abutment may perform its functions in substantially the 75 same manner where the opposite arrangement of material is employed, that is to say, where a rigid platen coöperates with yielding types and a yielding abutment.

I claim:—

1. In a machine of the type described, the combination, with a platen, a type-carrier substantially co-extensive with the length of the platen but provided with a series of type-lines each comprising characters 85 grouped so as to coöperate with substantially less than the entire length of the platen, and means for moving the type-carrier to bring its type-lines selectively into operative relation with the platen; of a stationary abutment fixed in position to be engaged, during the impressing operation, by the portion of the platen with which the types do not coöperate, so as to substantially equalize the working pressure upon the 95 platen during the production of an impression.

2. In a machine of the type described, the combination, with a platen faced with yielding material, a type-carrier substantially co-extensive with the length of the platen but provided with a series of type-lines of rigid material, each comprising characters grouped so as to coöperate with substantially less than the entire length of 100 the platen, means for moving the type-carrier to bring its type-lines selectively into coöperative relation with the platen, and means for inking the types in consequence of such movement; of a stationary abutment 105 fixed in position to be engaged, during the impressing operation, by the portion of the platen with which the types do not coöperate, so as to substantially equalize the working pressure upon the platen during 110 the production of an impression.

3. In a machine of the type described, the combination, with an elongated platen supported and actuated at the middle of its length, a type-carrier substantially co-extensive with the length of the platen but provided with a series of type-lines each comprising characters grouped so as to coöperate with a greater part of the length 120 of the platen at one side of its middle point than at the other side, and means for moving the type-carrier to bring its type-lines selectively into coöperative relation with the platen; of a stationary abutment fixed in position to be engaged, during the im- 125

pressing operation, by a portion of the platen with which the types do not coöperate, so as to substantially equalize the pressure against the platen on opposite sides of 5 its point of support.

4. In a machine of the type described, the combination, with a platen, a type-carrier provided with a series of type-lines all having blank intermediate spaces at corresponding points, and means for moving the type-carrier to bring its type-lines selectively into operative relation with the platen; of a stationary abutment fixed in position to occupy said blank space in 10 whichever of the type-lines is in position to be engaged by the platen.

5. In a machine of the type described,

the combination, with a platen, a type-carrier comprising a plurality of independently rotatable drums provided with type 20 arranged to form type-lines coöperable selectively with the platen, two of said drums being spaced apart from each other, and means for rotating the drums to bring their types selectively into operative position; of 25 a stationary abutment fixed in the space between said two drums, in position to engage the platen at that point.

In testimony whereof, I affix my signature in presence of two witnesses.
